UNITED STATES PATENT OFFICE.

CHARLES A. LATIENS, OF WORCESTER, MASSACHUSETTS.

CLASP.

1,233,255.

Specification of Letters Patent. Patented July 10, 1917.

Application filed October 28, 1915. Serial No. 58,351.

To all whom it may concern:

Be it known that I, CHARLES A. LATIENS, a citizen of the United States, and a resident of Worcester, in the county of Worcester, and State of Massachusetts, have invented certain new and useful Improvements in Clasps; and I do hereby declare the following to be a full, clear, and exact description of the invention, such as will 5 enable others skilled in the art to which it appertains to make and use the same.

My invention relates to clasps adapted for use in connection with hose and other garment supporters, and it consists in the 10 details of construction as will be more fully explained and pointed out in the claims.

In the accompanying drawings, Figure 1 is a view in perspective of my improvement. Fig. 2 is a view in section of the same, and Fig. 3 is a sectional view showing a modification.

1 represents the wire or other loop designed to be attached to the lower end of 25 a hose supporting strap, and 2 is the hose engaging loop, preferably struck up from sheet metal, and constructed to receive and retain the hose holding button in the usual and well known manner, and formed at its 30 upper end with a slot 2^a.

The loops 1 and 2 are connected by the metal plate 3, the ends 4 of which are bent around the adjacent cross bars of the two loops 1 and 2 and lock the parts together. 35 The upper cross bar of the loop 2 is non-circular in cross section, so that when the end of the plate 3 is bent around and clamped to said cross-bar, the loop 2 will be locked against free turning movement

40 in its bearing in the plate. The side edges 5 of the plate 3 are bent rearwardly at right angles for the purpose of stiffening the said plate and also for concealing the ends of the button carrying strap 6 which 45 is secured to and against the rear face of the plate.

The strap 6 is non-elastic, is doubled upon itself and its free ends placed against the rear face of the plate 3, pointing downwardly, and secured in such position by the teeth 7, preferably three, which are 50 cut out of the plate and are bent rearwardly and upwardly and engage the strap 6 above the free end of the latter as shown 55 in Fig. 2.

The free ends of the strap are inserted between the plate 3 and teeth 7 and the latter are then bent forwardly or toward the plate so as to clamp the strap against the plate, and its bearing in which the 60 loop 1 is mounted. The teeth 7 are pointed to engage and penetrate the strap, but the strap is locked primarily by the clamping action of the teeth.

The strap 6 is slightly longer than the 65 loop, and carries the button 8 which is secured to plate 9. This plate 9 is secured to the strap by the tooth 11 formed integral with said plate at the top thereof, which tooth penetrates one thickness of 70 the strap 6 and is upset against the rear face of the strap to prevent its withdrawal, and also by the ends 10 of the plate which are bent around the edge of one thickness of the strap.

75 The button is designed to enter the elongated loop and support and hold a hose or other garment that is engaged by the button in the usual and well known manner.

In the form of the invention shown in 80 Fig. 3, the teeth 7^a are made to project downwardly, instead of upwardly as shown in Figs. 1 and 2, and the non-elastic webbing, after having been clenched in place on the plate 3, is made to extend upwardly 85 and through the loop 1; then downwardly over the front of plate 3; then through the slot 2^a at the upper end of the loop 2, and then downwardly behind said loop, so that the button 8 may be in proper position relatively to the loop.

Having fully described my invention what I claim as new and desire to secure by Letters-Patent, is:

1. A garment supporter comprising upper and lower loops, a plate disposed between and connecting said loops, said plate having teeth struck up therefrom intermediate the loops and projecting rearwardly, a non-elastic strap one end of 95 which is inserted between the teeth and plate and held by the clamping action of said teeth and plate, and also by its engagement with the free ends of the teeth, and a button near the free end of the strap for coöperation 100 with the lower loop.

2. A garment support comprising a plate carrying a loop, the plate having rearwardly and upwardly projecting teeth struck up therefrom, a strap one end of 110

which is inserted between the teeth and plate and held by the clamping action of said parts, the said strap passing upwardly over the teeth and then down behind them
5 so as to engage the free ends of the latter, and a button carried by the strap for co-operation with said loop.

In testimony whereof, I have signed this specification in the presence of two subscribing witnesses.

CHARLES A. LATIENS.
